(57) **CLAIM**

The ornamental design for a pouch for tools, as shown and described.

DESCRIPTION

FIG. 1 is a perspective view of a pouch for tools showing our new design;

FIG. 2 is a front elevation view thereof;

FIG. 3 is a rear elevation view thereof;

FIG. 4 is a rear elevation view thereof showing an environmental belt;

FIG. 5 is a left side elevation view thereof;

FIG. 6 is a right side elevation view thereof;

FIG. 7 is a top plan view thereof; and,

FIG. 8 is a bottom plan view thereof.

The broken lines in FIGS. 3-8 showing a clasp illustrate portions of the pouch for tools and form no part of the claimed design. The broken line logo outline in FIGS. 1, 2, and 8 illustrate portions of a pouch for tools that form no part of the claimed design. The broken lines in FIG. 4 outlining a belt illustrate environment and form no part of the claimed design.
